UNITED STATES PATENT OFFICE.

ERNEST L. BROOME, OF TARRYTOWN, NEW YORK.

DAM CONSTRUCTION.

Application filed July 15, 1925. Serial No. 43,836.

This invention relates to the construction of dams for water power plants, and particularly to the location and arrangement of the sluiceways and gates, and the means for controlling the operation of the gates.

In the construction of water power plants, it is essential that provision be made for the maximum practical storage capacity, and also for the disposal of flood waters without damage to the plant, or to the riparian owners. Consideration must be given not only to the usual periodical flood, but also to the unusual or historical flood, which may perhaps occur once in a generation. The dam must be built on a secure foundation, and be able to withstand all possible destructive forces.

It is usually found, therefore, that the narrow rocky stretches of the water course afford better dam sites than the wide shallow stretches. It is frequently the case, however, that at the point where the foundation situation is best, the channel is too narrow to provide a sufficient length of dam crest to discharge the maximum flood, or at points where sufficient length of crest is obtainable the foundation conditions are questionable.

At the same time the cost of construction must be kept within the limit of profitable investment. The result is almost invariably a compromise between the longest possible crest or spillway, and the best foundations obtainable within the estimated cost. The historical flood, however, is always in the background, and it is usual to place in the crest or spillway so-called flood gates, which can, in case of need, be opened to take care of the dangerous surplus of water. These gates are frequently of large size, and quite often are frozen in solidly at a time when they are most needed, necessitating arduous and dangerous work to free them. Then too, they are often obstructed by floating débris, or are subjected to damage from masses of floating ice.

It should also be borne in mind that according to a well-known law of hydraulics, the velocity of discharge through an opening in the side of a reservoir is approximately proportional to the square root of the head, which is determined by the vertical distance between the center of the opening and the surface of the liquid in the reservoir. Obviously, therefore, for an equivalent dis-

charge, submerged openings will be much smaller in area than openings at the crest, with the net result that the necessary length of the dam and the quantity of masonry will be very materially reduced if the openings are submerged, and the number of apparatus units and the cost of construction will be much less.

It is customary to install submerged sluice gates in separate, retaining sections of dams, where the hoisting cables are not subjected to damage from ice or from floating objects, frequently carried by flowing water, as they would be if installed in spillway sections. With dams in which the spillway is of relatively small length, such as storage dams for water supply, the use of the retaining section is customary; and with dams in streams subject to large floods, the capacity of the spillway is a prime consideration and the elimination of the retaining section usually an important factor.

The restriction of the spillway due to the retaining section is often so important, that several devices have been proposed, enabling the installation of submerged gates in the spillway section, in which the operating mechanism is not subject to damage from surface conditions. However, such devices as have been heretofore used are difficult of access for inspection or repair without considerable expense or loss of stored water. I propose a submerged gate, so suspended and operated that it can be placed in the spillway section of a dam with its operating mechanism protected from surface conditions and at the same time be quickly removed for inspection or repair with minimum expense and minimum loss of stored water. My invention embodies the combination of a protected hoisting mechanism with a suspension providing a quick means of removal.

With the above facts in mind, therefore, the general object of the present invention is to provide an economical and practical construction in which submerged sluice gates are used in place of the usual so-called crest gates, thus permitting the discharge of a given amount of flood water through openings of minimum area. At the same time interference from freezing, or from floating ice or other flotsam is prevented, and the gates are always in operative condition, because all of the regular opening and clos-

ing mechanism is protected from freezing and from surface obstacles.

It is also an object of the invention to provide such a construction that the gate can be hoisted to the surface and removed for inspection or repair, when necessary, with a minimum loss of stored water.

Another object of the invention is to provide a construction of the type herein described in which the sluiceways, gates and operating mechanism therefor are so arranged that they do not interfere materially with the discharge of the spillway, or necessitate the construction of a longer spillway than is necessary to take care of the normal flow, as their length may run concurrently with the length of the spillway.

The invention also embodies various other distinctive features, the objects and advantages of which will be fully explained in connection with the accompanying drawings which illustrate the invention in its preferred form.

In the drawings:—

25 Figure 1 is a vertical section through a dam constructed according to my invention.

Figure 2 is an elevation looking from the inside of the reservoir with portions broken away and shown in section.

30 Figure 3 is a horizontal section through the sluiceways.

Figure 4 is a fragmentary section on an enlarged scale showing a portion of the mechanism for controlling the gates.

35 Figure 5 is a detail section showing a portion of the means for supporting the gates, and for lifting them out for inspection.

Referring in detail to the drawings, the main part of the masonry structure 10 is of the usual shape, and may be provided at its crest with a flash board 11, such as is generally used in dams of this character. The base of the structure 10 is provided with a plurality of sluiceways 12 extending longitudinally therethrough, and each provided at its inlet end with a seat 13, on which is seated a sluice gate 14. The gate is preferably of the caterpillar type, mounted on wheels or rollers, similar to that shown in my U. S. Patent 1,306,370, issued June 10, 1919, and the seat 13 is slightly inclined so that the vertical component of the pressure on the movable gate together with the weight of the movable gate and its attachments are the sole forces acting to close the gate. The structure of the gate itself forms no part of the present invention, and a detailed description thereof is unnecessary.

For the purposes of the present invention, it is sufficient to note that the gate 14 is suspended at the bottom of a hoistway 15, which extends from the sluiceway 12 to the crest of the dam, and may be vertical as shown, or at any preferred angle. One or more sheaves 16 are mounted on the up-

per side of the sluice gate, and a hoisting cable 17 passes about these sheaves and other sheaves 18, which are mounted at the lower end of a jointed suspension member 19. The member 19 is supported at its upper end by a frame 20, which rests in pockets 21 formed at the top of the hoistway 15. The other end of the cable 17 passes between two spaced sheaves 22 and 23 mounted in a recess 24, which is formed in the side of the hoistway 15 sufficiently below the crest of the dam to prevent freezing. From the recess 24, the cable 17 passes in an inclined direction upwardly through a conduit 25 formed in or set in the masonry, and over a sheave 26 to a winding drum 27 driven by hand power or other well known motor.

The drum 27 and sheave 26 are mounted on a platform or bridge 28, which is supported on the spillway above the maximum high water by pillars 29.

The upper end of the hoistway 15 is closed by a cover plate 30, whose upper surface conforms to the surface of the spillway and is flush therewith, and which may be removed when it is desired to withdraw the gate for inspection or repairs. The upper end of the suspension member 19 is formed with an eye 31, adapted to be engaged by a hook, so that the gate may be raised by means of any suitable structure or crane 32 situated on the platform 28. When the gate is thus removed, the cable 17 is prevented from chafing by the sheave 23. Small holes 33 are formed in the cover plate 30, and similar holes 34 are formed through the masonry wall in front of the hoistway 15, so that the water pressure may be equalized at all times.

The entrance to the sluiceway 12 may be protected by a grating 35, and the edges of this entrance opening are rounded, as shown at 36, so as to form the least resistance to the flow of water therethrough. The top edge 36 is slightly lower than the top bar of the frame 13, and the distance between the side edges 36 is slightly less than the width of the gate opening, as best shown in Figure 3, so that a prism of water flowing into the mouth of the sluiceway will not impinge against the sharp edges of the gate opening to form eddy currents which would impede the flow.

It has been observed that wherever the water passes through a restricted channel or sluiceway, under a considerable head, that the surface erosion near the entrance to the sluiceway is excessive. This erosion is generally believed to be the result of the formation of a partial vacuum due to the contraction of the escaping jet. In order to prevent such destructive action, a recess 37 is formed entirely around the sluiceway, and this recess is connected to the atmosphere by a vent pipe 38, so that atmospheric pressure is al-

ways maintained within the sluiceway, and erosion is thereby practically eliminated.

From the foregoing description it will be appreciated that as much water can be 5 discharged through the submerged gates as could be discharged through surface flood gates having an area several times as large. By the construction herein described, the submerged gates are easily operated, and 10 10 may be easily removed for inspection or repairs. Their operation is entirely independent of surface conditions, and cannot be interfered with by floating ice or débris, and cannot freeze in. In very severe weather, 15 15 the conduit 25 may be filled with oil to prevent any possibility of freezing therein.

It should be further noted that the arrangement herein described presents the 20 novel possibility of installing submerged 20 gates in the spillway of the dam, the discharge through the gates supplementing the discharge over the spillway. It is customary to install submerged gates in a section 25 separate from the spillway of a dam, where the hoisting and suspension mechanism is removed from the flow of water, thus greatly increasing the cost of construction, and making it necessary to choose the dam site where a sufficient length of dam could be 30 obtained. With my arrangement, the submerged gates do not add to the length of the dam, and the hoisting and suspension mechanism is protected from the flow.

While I have shown and described in detail 35 the specific arrangement, which appears at present to be preferable, it is quite apparent that various modifications may be made in the construction and arrangement of the various parts without sacrificing any of 40 the material advantages of the invention. It is my purpose, therefore, to include all such modifications within the scope of the appended claims.

What is claimed is:—

45 1. In a dam, the combination of a masonry structure having a spillway over its crest and having a sluiceway therethrough below the crest, a gate for said sluiceway, a hoistway extending upwardly from the gate 50 through the masonry, a passageway extending laterally and upwardly from a point in the hoistway where there is no danger of freezing, a hoisting device supported above said passageway, and a cable extending 55 through said passageway and into said hoistway for suspending the gate and connected at one end to said hoisting device and operable thereby to open or close the gate.

60 2. In a dam, the combination of a masonry structure having a spillway over its crest and having a sluiceway therethrough below the crest, a gate for said sluiceway, a hoistway extending upwardly from the gate 65 through the masonry, a passageway extending laterally and upwardly from a point in

the hoistway where there is no danger of freezing, a hoisting device supported above said passageway, a cable extending through said passageway and into said hoistway for suspending the gate and connected at one 70 end to said hoisting device and operable thereby to open or close the gate, a suspensional member connected to the other end of the cable, and means connected with said suspensional member for raising the gate 75 up through the hoistway for inspection or repairs.

3. In a dam, the combination of a masonry structure having a spillway over its crest and having a sluiceway therethrough below the crest, a gate for said sluiceway, a hoistway extending upwardly from the gate through the masonry, a platform located directly over the spillway, pillars supporting said platform, one of said pillars being 80 centered approximately over the center of the gate, a hoisting device mounted on the platform, a cable located partly in said hoistway for suspending the gate and connected at one end to said hoisting device and operable thereby to open or close the gate, a suspensional member connected to the other end of the cable, and means connected with said suspensional member for raising the gate 85 up through the hoistway for inspection or repairs.

4. In a dam, the combination of a masonry structure having a spillway over its crest and having a sluiceway therethrough below the crest, a gate for said sluiceway, a hoistway extending vertically upwardly from the gate through the masonry, the upper portion of said hoistway being enlarged to form pockets, a frame resting in said pockets, a suspensional member supported by said frame, an inclined passageway extending laterally and upwardly from a point in the hoistway below said pockets, a hoisting device supported above said passageway, and a cable supported at one end by the suspensional member, its other end extending upwardly through said passageway and being connected to the hoisting device, the intermediate portion of said cable being operatively connected to the gate, whereby the latter may be opened or closed.

5. In a dam, the combination of a masonry structure having a spillway over its crest and having a sluiceway therethrough below the crest, a gate for said sluiceway, a hoistway extending vertically upwardly above the gate through the masonry, the upper portion of said hoistway being enlarged to form pockets, a frame resting in said pockets, a cover for the hoistway conforming to the superficial contour of the spillway, a suspensional member supported by said frame, an inclined passageway extending laterally and upwardly from a point in the hoistway below said pockets, a platform lo- 125 120 130

cated directly over the spillway, pillars supporting said platform, a hoisting device mounted on the platform above the upper end of said inclined passageway, a cable located partly within the hoistway and supported at one end by said suspensional member, the other end of the cable extending upwardly through said passageway and connected to the hoisting device, the intermediate portion of said cable being operatively connected to the gate, whereby the latter may be opened or closed.

6. In a dam, the combination of a masonry structure having a spillway over its crest and having a sluiceway therethrough below the crest, a gate for said sluiceway, a hoistway extending vertically upwardly from the gate through the masonry, the upper portion of said hoistway being enlarged to form 20 pockets, a frame resting in said pockets, a suspensional member supported by said frame, an inclined passageway extending laterally and upwardly from a point in the hoistway below said pockets, a hoisting device supported above said passageway, a cable supported at one end by the suspensional member, its other end extending upwardly through said passageway and being connected to the hoisting device, the intermediate portion of said cable being operatively connected to the gate, whereby the latter may be opened or closed, and means for engaging the suspensional member to lift the same and thereby lift the gate out 35 of the hoistway for inspection or repairs.

7. In a dam, the combination of a masonry structure having a spillway over its crest and having a sluiceway therethrough below the crest, a gate for said sluiceway, a hoistway extending vertically upwardly above the gate through the masonry, the upper portion of said hoistway being enlarged to form pockets, a frame resting in said pockets, a suspensional member supported by 40 said frame, an inclined passageway extending laterally and upwardly from a point in the hoistway below said pockets, a platform located directly over the spillway, pillars supporting said platform, one of said pillars being centered approximately over the center of the gate, a hoisting device mounted on the platform above the upper end of said inclined passageway, a cable located partly within the hoistway and supported at one 45 end by said suspensional member, the other end of the cable extending upwardly through said passageway and connected to the hoisting device, the intermediate portion of said cable being operatively connected to the gate, 50 whereby the latter may be opened or closed, and lifting means supported by the platform and engageable with the suspensional

member to lift the same and thereby lift the gate out of the hoistway for inspection or repairs.

8. In a dam, the combination of a masonry structure having a spillway over its crest and having a sluiceway therethrough below the crest, a gate for said sluiceway, an inclined frame on which the gate is normally held seated by the downward as well as the lateral pressure of the water above the dam, a platform located directly over the spillway, pillars supporting said platform, one of said pillars being centered approximately over the center of the gate, a hoisting device mounted on the platform, and a cable connecting the gate to the hoisting device and operable by the latter to raise or lower the gate.

9. In a dam, the combination of a masonry structure having a spillway over its crest and having a sluiceway therethrough below the crest, a gate for said sluiceway, an inclined frame on which the gate is normally held seated by the downward as well as the lateral pressure of the water above the dam, a hoistway extending upwardly from the gate through the masonry, a platform located directly over the spillway, pillars supporting said platform, one of said pillars being centered approximately over the center of the gate, a hoisting device mounted on the platform, and a cable extending through a portion of said hoistway and connecting the gate to the hoisting device and operable by the latter to raise or lower the gate.

10. In a dam construction, a submerged sluice near the base thereof and arranged below the spillway; a gravity sluice gate adapted to be lowered to seal the sluiceway; operating mechanism for the sluice gate including a cable so arranged that it is not exposed to flowing water in the spillway; a hatch-way in the dam opening through the crest in the spillway; and suspending means for the sluice gate in the hatch-way.

11. In a dam construction, a submerged sluice arranged below the spillway; a substantially vertical hatch-way above the mouth of the sluice and having a cover at the crest of the spillway; a sluice gate adapted to seal the mouth of the sluice suspended below the hatch-way cover; a hoisting cable connected to the suspending means for the sluice gate and projecting through a portion of the dam where it is not subject to damage by floating objects or to freezing; and a hoisting means accessibly arranged to raise and lower the sluice gate.

In testimony, that I claim the foregoing as my own, I have hereto affixed my signature.

ERNEST L. BROOME.
